UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,353,110.

Specification of Letters Patent. Patented Sept. 14, 1920.

Application filed January 16, 1920. Serial No. 351,783.

To all whom it may concern:

Be it known that I, FRED S. CARR, a citizen of the United States, and resident of Newton, in the county of Middlesex and 5 Commonwealth of Massachusetts, have invented an Improvement in Separable Fasteners, of which the following description, in connection with the accompanying drawings, is a specification, like characters on 10 the drawings representing like parts.

This invention pertains to improvements in separable fasteners.

It is among the objects of the invention to provide a fastener of simple and rugged 15 construction, providing a considerable degree of holding power, especially against forces resultant from lateral strain.

In the drawings, which show a preferred embodiment of one form of my invention:

20 Figure 1 is an elevation of two pieces of fabric secured together by a preferred form of fastener;

Fig. 2 is a section on the line 2—2 of Fig. 1;

25 Fig. 3 is a plan view of two pieces of fabric secured together by a plurality of such fasteners;

Fig. 4 is a front elevation of the preferred form of socket member; and

30 Fig. 5 is an elevation of the preferred form of spring.

Referring to the drawings and to the preferred form of my invention selected for 35 illustrative purposes, I have shown a stud 6 which may be secured to a stud-carrying fabric 7 in any suitable way, but preferably by engagement of the stud base 8 within a flanged-over stud-securing part 9, the stud-securing fabric being gripped between the 40 base 8 and the stud-securing part 9.

The preferred form of socket herein illustrated includes a casing 10 containing a spring 11, which is preferably stamped from sheet metal to provide a stud-receiving aperture 12 and providing a slot or opening 13 to permit expansion of the spring to receive the stud.

45 The spring 11 is also preferably provided with projections 14 and 15 spaced apart and 50 located opposite the spring opening 13. These projections 14 and 15 abut against the casing 10 when strain is exerted to bring

the stud against the spring at a position midway between these projections, any yielding of the spring between these projections tending more firmly to hold together the sides of the slot 13 of the spring, thereby more closely to embrace the stud. It is obvious that the projections 14 and 15 may be provided on the casing instead of on 60 the spring, if desired.

I also preferably provide projections 16 and 17 located on opposite sides of the opening 13 and adapted to space the spring from its casing. The projections 14, 15, 16 and 17 65 are of such length that they will not interfere with the casing in such a way as to prevent the entrance and disengagement of the stud in the usual and desired manner.

The projections 16 and 17 are, however, 70 preferably proportioned so that they will bear against the casing in such a way as to prevent excessive opening of the spring when strain is exerted in such a direction as to bring the stud into forcible engagement 75 with that side of the spring adjacent the opening 13. This action may be somewhat facilitated and the security of the lateral lock somewhat improved by providing a notch 18 opposite the opening 13 of the 80 spring, this notch preferably having its opening somewhat narrower than the stud so that the points 19 and 20 will engage the neck of the stud under the lateral strain last described. If desired, rotation of the spring 85 in the socket may be prevented by any suitable way, herein typified by the spring-locating part 21, which may be struck downwardly from the casing flange.

The preferred form of socket hereinbefore described may be secured to its carrying fabric 22 in any suitable way, but preferably by a tubular projection 23 adapted to be deflected outwardly by anvil portions on a socket-securing cap 24 and to engage behind lips 25 on the socket-securing cap.

It will be understood that I use the word "fabric" in its broader sense to include not only woven materials, but any flexible carrying medium.

100 While I have shown and described a preferred form of one embodiment of my invention, it will be understood that a number of changes involving omission, substitution,

alteration and reversal of parts, and even changes in the mode of operation, may be made without departing from the scope of my invention, which is best defined in the 5 following claims.

Claims:

1. A separable fastener comprising, in combination, a stud having a head and a neck; a socket including a casing, a flat 10 spring in the casing, said spring having a stud-receiving opening, a split at one side of said opening; and spacing means for spacing the spring from the casing at a point opposite the split in the spring, where- 15 10
15 by strain on the spring in a direction away from the split will tend to hold the spring closed and to increase the holding power of the spring on the stud.
2. A separable fastener comprising, in combination, a stud having a head and a neck; a socket including a casing, a flat spring in the casing, said spring having a stud-receiving aperture therethrough and having a slit, and a notch communicating 25 with said aperture.
3. A separable fastener comprising, in combination, a stud having a head and a neck; a socket including a casing, a flat spring in the casing, said spring having a stud-receiving aperture therethrough and having a slit, and a notch communicating 30 with said aperture, said notch adjacent said slit.
4. A separable fastener comprising, in combination, a stud having a head and a neck; a socket including a casing, a flat spring in the casing, said spring having a stud-receiving aperture therethrough and having a slit, and a notch communicating 35 with said aperture, said notch adjacent said slit, said casing and spring providing abutting surfaces opposing opening of the

spring when strain is exerted between stud and socket in the direction of said slit.

5. A socket for separable fasteners comprising, in combination, a casing, a flat spring in the casing, said spring having a stud-receiving aperture and having a slit at one side thereof, and two projections between spring and casing, one on either side 50 of and adjacent the slit.

6. A socket for separable fasteners comprising, in combination, a casing, a flat spring in the casing, said spring having a stud-receiving aperture and having a slit 55 at one side thereof, and two projections between spring and casing, said projections spaced apart and located opposite the slit in the spring.

7. A socket for separable fasteners comprising, in combination, a casing, a flat spring in the casing, said spring having a stud-receiving aperture and having a slit at one side thereof, and two projections between spring and casing, one on either side 60 65 of and adjacent the slit, and two other projections between spring and casing, said other projections spaced apart and located opposite the slit in the spring.

8. A socket including a casing, a flat spring in the casing, said spring having a stud-receiving aperture and having a slit at one side thereof, said spring provided with a plurality of external bosses to space the body of the spring from the casing when 70 75 under lateral strain, said bosses proportioned to permit expansion of the spring in the casing to permit the stud to be inserted in and removed from the stud-receiving aperture.

In testimony whereof I have signed my name to this specification.

FRED S. CARR.
